ANTISIPHONING DEVICE

William E. Moreland, Atlanta, Ga., assignor of
one-third to Charles E. Flowers and one-third
to Warner V. Flowers, Atlanta, Ga.

Application May 9, 1932. Serial No. 610,288

1 Claim. (Cl. 220—86)

This invention relates to fuel tanks, and its general object is to provide an anti-theft device primarily designed for the fuel tanks of motor vehicles, that will prevent the siphoning of fuel therefrom, yet will in no way interfere with the filling of the tanks.

A further object of the invention is to provide an anti-theft device and filling spout for fuel tanks that will prevent the taking of fuel therefrom, and which is simple in construction, does not include locks or the like, is inexpensive to manufacture and extremely efficient for the purpose intended.

This invention also consists in certain other features of construction and in the combination and arrangement of the several parts, to be hereinafter fully described, illustrated in the accompanying drawing and specifically pointed out in the appended claim.

20 In describing my invention in detail, reference will be had to the accompanying drawing wherein like characters denote like or corresponding parts throughout the several views, and in which:

Figure 1 is a fragmentary sectional view taken 25 through a fuel tank with my device applied thereto.

Figure 2 is a fragmentary top plan view.

Figure 3 is a view similar to Figure 1 of a modified form.

30 Referring to the drawing in detail, and particularly to Figures 1 and 2, it will be noted that the fuel tank is indicated by the reference numeral 1 and extending through one vertical wall thereof is a tubular member 2 which is substantially oval shape in cross section and curved 35 upon itself in a manner to provide a gooseneck.

The inner end of the tubular member terminates adjacent the top of the fuel tank and is provided with an extension 3 in the form of a 40 tongue that is disposed in close proximity to the top as clearly shown in Figure 1. The outer end of the tubular member terminates in a plane above the top of the tank and as the tubular member provides the filling spout for the tank, 45 the outer end has secured thereto and following the circumferential curvature thereof collar pieces 4 to receive the cap 5 which is of the usual construction and is provided with a vent opening as shown, as well as a gasket.

50 Arranged in the tubular member is a vent pipe 6 which follows the longitudinal curvature thereof and has its outer end terminating adjacent the outer end of the tubular member, while its inner end is bent at an angle upon itself to provide a horizontal portion 7 which is arranged in contacting engagement with the top of the tank and terminates in a downturned end 8.

In Figure 3 I have illustrated a modified form 60 of my invention which in fact is an attachment for fuel tanks now in general use. The tank in

Figure 3 is indicated by the reference numeral 9 and includes the usual filling spout 10 that is provided with a cap 11.

The attachment includes only a tubular member 12 which is likewise in the form of a gooseneck and has one of its ends terminating adjacent the top of the tank 9 and this end is also provided with an extension 13 similar to the extension 3 and which likewise is disposed in close proximity to the top as shown.

70 The opposite end of the tubular member 12 extends into the filling spout 10 and is riveted or otherwise secured thereto through the medium of suitable securing means 14. The diameter of the tubular member 12 is less than the diameter of the filling spout 10, with the result a space 15 is provided and which acts in the capacity as an air vent.

75 From the above description and disclosure of the drawing, it will be obvious that I have provided an anti-theft device for fuel tanks that will prevent the siphoning of fuel therefrom, but at the same time will not interfere with the proper filling of the tanks. It is true that a 80 siphoning tube can be disposed within the tubular member, but by providing the extension at the inner end of the tubular member and arranging the inner end and extension in close proximity to the top of the tank it is impossible to dispose a siphoning tube within the fuel in the tank, and 85 of course the space 15 is of a size to prevent the insertion of a siphoning tube therethrough, with the result I have provided a very simple but efficient device to prevent the theft of fuel from tanks and especially the tanks of motor 90 vehicles.

95 It is thought from the foregoing description that the advantages and novel features of my invention will be readily apparent.

I desire it to be understood that I may make 100 changes in the construction and in the combination and arrangement of the several parts, provided that such changes fall within the scope of the appended claim.

105 What I claim is:

An anti-siphoning device for a fuel tank comprising a curved tubular member having one end arranged in said tank and terminating adjacent the top thereof, a tongue formed with said end and disposed in close proximity to said top, said tubular member constituting the filling means for the tank and having its opposite end extending exteriorly thereof, a cap for the last mentioned end, and a vent pipe arranged within said tubular member and following the longitudinal curvature thereof.

WILLIAM E. MORELAND.
